UNITED STATES PATENT OFFICE.

SHIRLEY S. WEEKS, OF OAKLAND, CALIFORNIA.

AUTOMATIC GAS-ANALYZER.

1,345,047.

Specification of Letters Patent. Patented June 29, 1920.

Application filed January 27, 1919. Serial No. 273,433.

To all whom it may concern:

Be it known that I, SHIRLEY S. WEEKS, a citizen of the United States, residing at Oakland, in the county of Alameda and State of California, have invented certain new and useful Improvements in Automatic Gas-Analyzers, of which the following is a specification.

This invention relates to improvements in automatic gas analyzers of the type in which at predetermined intervals a gaseous mixture is held in a closed chamber, the gas which it is desired to determine absorbed by suitable means and the resultant reduction of pressure indicated, or recorded as a percentage of the original inclosed volume.

The present invention has more particularly to do with the apparatus for collecting and tightly inclosing a sample of mixed gases at atmospheric pressure and to bring the sample into contact with suitable chemicals for absorbing the gas, the percentage of which it is desired to determine. The present apparatus has special reference to the determination of carbon dioxid in boiler flue gas by absorption in a solution of potassium hydroxid.

The principal object of the invention is to provide an automatic apparatus for performing the functions above outlined which will be reliable in operation and which will give results having a high degree of accuracy.

Another object of the invention is to simplify the apparatus by utilizing a piston for separating the absorbent solution from the gases during the period in which fresh gases are being taken into the apparatus, and to further utilize the same piston for forcing the inclosed volume of gas into contact with the absorbent solution without the usual losses due to end clearances and leakage past the piston. In my device the solution, piston and gases are tightly held in one chamber and hence no losses occur in transferring the gas from the measuring chamber into contact with the absorbent solution.

Another object of the invention is to construct and operate the piston so that movement thereof conveys the absorbent solution into contact with the gas, but the absorbent solution will not by such movement be conveyed to the walls of the inclosing chamber, thereby preventing absorption prior to the time the required volume is inclosed.

A further object of the invention is to so arrange the piston and associated mechanism that the amount of residual gas retained on the opposite side of the piston during the measuring and absorbing periods respectively will be a minimum and always of the same amount. This enables the recording or indicating instrument to be calibrated to compensate for the slight errors which would otherwise be introduced by the residual amount of gas.

A still further object of the invention is to utilize a fan or similar mechanical means for supplying the gaseous mixture to the device, making it practical to displace a large volume of gas. This assures a fresh supply of gas directly from the source thereof for each analysis regardless of the length of pipe connecting the device to the source of gas.

In general I aim to provide a device of the character set forth which is mechanically simple in construction but which is accurate in operation, and which will continuously at periodical intervals perform the cycle of operations necessary to determine the percentage of the desired constituent of the gaseous mixture.

With these and other objects in view, the invention consists of certain novel features of construction, combinations and arrangements or parts hereinafter described and more specifically pointed out in the appended claims; it being understood that changes in form, proportion, size and minor details of construction within the scope of the claims may be resorted to without departing from the spirit of the invention or sacrificing any of the advantages thereof.

References being had to the drawings forming a part of the specification:

Figure 1 is a view in front elevation of my improved analyzing device.

Fig. 2 is a view in plan of the same.

Fig. 3 is a view in section through the solution container, the measuring chamber and the valve mechanism.

Referring to corresponding parts by the same numerals of reference, 1 denotes a base plate, having a bracket 2 by which it may be attached to a wall or other supporting surface. Or if the device is for portable use, feet may be provided for standing it on a horizontal surface.

Attached to the underside of plate 1 is the air tight solution container denoted by

3 which consists of the cylindrical vessel 4 having a removable cover plate 5. Extending upward from the cover plate is a tubular upright 6 which is closed at its upper end and which passes through a hole 7 in the base plate 1.

Within the container 3 at one side is a lug 8, and on the outside is a lug 9, these lugs being provided with alining openings, 10 in which the shaft 10 is oscillatively mounted. On the outside of the lug 9, a stuffing box 11 is provided around the shaft while within the container an arm 12 is attached thereto. This arm extends to the center of 15 the container where the end is bifurcated and straddles the guide rod 15. The latter has its lower end in threaded engagement with an opening in hub 14, is arranged coaxially with the container and extends a 20 short distance into the tubular portion 6.

Slidably mounted on the lower end of the rod 15 is a sleeve 16 to which is attached a spider 18 which carries an agitator 17. The hub of this spider is so positioned that it is 25 engaged by the end of arm 12. Above sleeve 16 is a long perforated sleeve which is slid- 30 able on the guide bar 15. This sleeve has a float 20 attached to its upper end and a smaller float 21 to its lower end. The floats are thus held in spaced relation by the sleeve and stretched between their adjacent faces 35 is a plurality of chains 22 which have an open type link. The upper float 20 is concentric with the bore of upright 6 but of smaller diameter and has attached to its upper end a piston 23 which divides the 40 space in the upper end of the upright into two chambers.

The float 20 has an opening 25 extending 45 longitudinally therethrough, the upper end of which communicates with an opening in the piston and which forms a seat for the ball plug from which extends a small tube 29, the bore of which serves as a guide for the 50 stem 30 which extends from the ball 27. A very light spring 28 is interposed between the plug and the ball and holds the latter on its seat. Extending from opening 25 to the annular space around float 20, is a passageway 55 26 and extending the entire length of the interior wall of the upright 6 is a small groove 26'.

On the upright 6 are lugs 31, 32 and 33 all 60 of which have openings communicating with the interior of this upright. To the first of the lugs is attached an indicating or recording vacuum gage (not shown). As I deal with a volume of gas in an inclosed chamber the removal of one of its constituents will cause a reduction of pressure and I 65 calibrate my gages so that this reduction of pressure is read as a percentage of the original volume of the sample of gas.

To the lugs 32 and 33 are attached valve 65 casings 34 and 35 respectively, each of which

is provided with a bore that communicates with the interior of upright 6. Casing 34 has a side branch 36, while casing 35 has two adjacent branches 37 and 38 and a third side branch 39 spaced somewhat farther away. 70 The side outlet 39 is connected with 36 through a gas tight member 40, which has an interior cavity of comparatively large volume. Within the bore of casing 34 is a tight fitting piston 42 and in threaded engagement with the outer end of the casing is a sleeve 41. The valve stem 43 on which the piston is attached extends through the closed end of sleeve 41 and within the latter is provided with an abutment 44. A spring 45 is interposed between this abutment and the end of the sleeve, tending thus to force the piston to its closed position.

Likewise in threaded engagement with the outer end of valve casing 35 is a similar 85 sleeve 46 and extending therethrough into the bore of the casing is a rod 47. This rod has a spring 48 which tends to move the rod toward the upright and on this rod are mounted two pistons 50 and 51 which are 90 spaced at such a distance as to control the flow of gas through the side branches of this valve in the manner hereinafter described. Sleeve 46 has a small opening 35' which when the valve is closed places the interior 95 of connection 40 in communication with the atmosphere.

It will be noted that the ends of the valve casings which enter the supporting lugs are provided with orifices 52 and 52' which are 100 smaller than the bores of the casings thereby forming shoulders 53. Pistons 42 and 51 have the valve stem extending through them an amount equal to the length of these orifices which have a diameter only slightly 105 larger than the ends of the valve stem. The pistons themselves are faced as shown at 54 with material which will make a tight joint when in contact with the shoulders 53.

The driving mechanism for the valves and arm 12 comprises a motor 60 which is connected to a shaft 61 through a flexible coupling 62. This shaft is revolvably mounted in journals 63 between which a threaded worm 64 is attached to the shaft. The latter extends to the opposite side of the plate where it drives the fan or air pump 65.

Above shaft 61 and at right angles thereto is another shaft 66 which is revolvably mounted in journals 67 and has attached thereto a worm wheel 71 and a toothed spur pinion 68. The former is engaged by the worm 64 while the latter meshes with a toothed gear 69 attached to the shaft 70. This shaft is revolvably mounted in journals 72 and has attached thereon cams 73, 74, and 75.

Cam 73 is engaged by a roller 80 on arm 76, one end of which is pivotally mounted as at 77, while the other end is pivotally 130

attached to a connecting link 78, the lower end of which is in turn connected to the arm 79 on shaft 10. Cam 74 reciprocated a rod 81 which is slidably mounted in a bracket 82 and has its direction of movement parallel to the valve rod 47, to which it is connected by an arm 83. Cam 75 reciprocates a rod 84 which is parallel to valve rod 43 and connected thereto by the arm 85. 5 Rod 84 is slidably mounted in bearings 86, and as here illustrated this rod is provided with a forked head 87 having a pivotally mounted roller 88. A spring 89 is interposed between the back of this head and the adjacent bearing to hold the roller in contact with the associated cam. In like manner rod 81 has a forked head 93 containing a roller 94 for contact with the cam 74 and this roller is urged toward the cam by a 10 spring 95.

The intake opening of the fan is connected to the side branch 38 by means of a tube 90, while from branch 37 a tube 91 extends to the source from which the sample of gas 15 for analysis is to be obtained. The top plate 5 is provided with a filling tube 92 which is so arranged that by filling to a given mark, the solution within the upright portion 6 will be at a predetermined level.

20 The operation is as follows:

The motor 60 continuously rotates the shaft 61 and thus drives the fan 65 at high speed and by means of the various gears drives the shaft 70 at a much slower speed.

25 In the drawings, the apparatus is illustrated with all valves open, and in this condition the suction produced by the fan 65 draws gas through the tube 91 which is connected to the source of gas, through the side branch 37, the orifice 52' into the chamber above the plunger 20. From this cavity the gas passes through the orifice 52, valve casing 34, through the side outlet 36, the gas tight member 40, the side branch 39, through the 30 casing 35 between pistons 50 and 51 and then through the side branch 38 and hose 90 to the intake of the fan. Thus during the time the valves are so positioned, a continuous stream of gas is being drawn 35 through the chamber above the plunger. Groove 26' is provided so that there is no danger of the piston sticking in its upward position and so that no pressure is accumulated below the piston when it passes below 40 opening 52. The lateral passageway 26 is provided for the same purpose in respect to the space in opening 25.

45 After a predetermined interval cam 74 permits the springs 95 and 48 to move the rods 47 and 81 to the right as viewed in Fig. 2. This closes the orifice 52', connects the passageway in the side branch 39 with the atmosphere, closes passage in branch 39 from that in 38, and connects the passageways of side branches 37 and 38 with each

other, thus permitting the fan to continue drawing gas through the tubes 90 and 91. At a predetermined interval after valve 54 is closed, cam 75 permits the springs associated with rods 43 and 84 to move these 50 rods to the left as viewed in Fig. 2 and thus causes the piston 42 to close the orifice 52. There is an appreciable interval between the closing of orifice 52' and the closing of the passageway in branch 36 by piston 42, the 55 object of which is to allow the gas in the chamber above the piston to come to atmospheric pressure as otherwise it would be at slightly less pressure due to the fan suction in drawing the gas through the apparatus. 60 In order to secure uniform results it is necessary that the gas analyzed be brought to atmospheric pressure which is accomplished by the delayed closing of valve 34. After the orifice 52' is closed the passageway in 65 branch 36 remains unclosed by piston 42 a sufficient length of time that atmospheric pressure entering through the hole 35' into connection 40 may force the gas within the latter into the measuring chamber, bringing the pressure therein to that of the atmosphere. The volume of 40 is so large in comparison with the amount of gas necessary to bring the inclosed gas to atmospheric pressure that there is no danger of 70 air being forced into the measuring chamber.

75 After the piston 42 has closed the orifice 52, cam 73 moves the arm 76 in a downward direction, thereby raising the arm 12 within 100 the container 4. The movement of this arm raises the spider 18 and the attached member 17 and the upper end of sleeve 16 contacts with the bottom of sleeve 19, thereby raising this sleeve and the floats on the top and bottom thereof. As the piston 23 is raised the gas which is above the same passes through the valve 27 and groove 26' into the cavity below the piston and float. This movement of the plunger continues until 105 the flat upper surface of the piston is in contact with the top wall of the upright portion 6, and substantially all the gas is in the space below the said plunger. This upward movement raises the chains 22 out of the 110 solution, each link carrying with it a globule of the absorbing chemical. The solution thus carried by the chain presents a large surface in contact with the gas so that the particular gas to be determined is quickly 115 absorbed. The plunger remains in its upper position during substantially one-half of the cycle of operation giving ample time for complete absorption and while in this position the passageway of lug 31 is in communication with the space below the piston, and thus the reduction in pressure due to the absorption of the given constituent of 120 gas is indicated by a suitable gage or meter attached to the opening of this lug. 125

After an interval sufficient to permit the complete absorption of the given gaseous element, the cams are arranged to move their respective contact members in the opposite direction and thus to open the valves 34, 35 and to move down arm 12.

It will be noted that the spider 18 is not attached to the arm 12 and that sleeve 19 is not attached to sleeve 16. Thus these 10 parts are free to move downwardly independent of the movement of the arm. The weight of the piston, floats and attached part is such that the piston always floats at a given distance above the solution, and 15 therefore the gas trapped beneath the piston is of the same volume each operation. The space between the upper end of the sleeve 16 and the lower end of sleeve 19 allows for a drop in the level of the solution without 20 affecting the relation of the float with respect to the solution level.

The solution is agitated by the up and down movements of the member 17 so that a uniform strength is maintained. The normal 25 solution level is as indicated.

It will be understood that no exact solution level or position for the plunger is required as the reduction in pressure is independent of the volume of gas acted upon.

30 The shape of float 20 is such that capillary attraction will not draw the solution up between the piston and walls of the cylinder. This keeps the walls of the measuring chamber dry and hence the gas does not come into 35 contact with the absorbing chemical before the various valves are closed, and the piston moves upwardly. At the same time the shape of the float is such that a minimum clearance volume is provided below and this 40 is independent of the level of the solution, due to the fact that the plungers and associated parts float therein.

I claim as new and wish to cover by Letters Patent:—

45 1. A gas analyzer comprising a vessel for holding an absorbent material, said vessel having a chamber above said material for inclosing a gaseous mixture, a piston normally separating the contents of said chamber from said material, means within said vessel for operating said piston, and by-pass means for passing the contents of said chamber to the opposite side of said piston for contact with said absorbent material.

50 2. A gas analyzer comprising a vessel for holding an absorbent material, said vessel having a chamber adjacent to said material for holding a gaseous mixture, a floating piston normally separating the contents of 55 said chamber from said absorbent material, means below the surface of said solution for moving said piston and normally disconnected therefrom, and by-pass means for passing the contents of said chamber to the 60 opposite side of said piston.

3. A gas analyzer comprising a vessel for an absorbent solution, a chamber above said solution for inclosing a gaseous mixture, a piston in said chamber normally separating the contents thereof from said solution, means extending through said solution for moving said piston through said chamber, and by-pass means to permit the contents of said chamber to flow to the opposite side of said piston for contact with said solution. 70

4. A gas analyzer comprising a vessel, an absorbent solution held therein, a tubular portion on said vessel, having a cavity for inclosing a gaseous mixture, a piston, means passing through said solution for moving 80 said piston longitudinally of said cavity, and by-pass means to permit the passage of said mixture from one side of the piston to the other.

5. A gas analyzer comprising a closed 85 vessel, an absorbent solution therein, a tubular portion on said vessel forming a chamber for inclosing a gaseous mixture, a piston movable longitudinally of said chamber, by-pass means to permit the passage of the 90 gaseous mixture past said piston, said tubular portion having orifices to permit a flow of gas through said chamber, and valve means for closing said orifices and entirely filling the portion thereof which communi- 95 cates with said chamber.

6. A gas analyzer comprising a tubular vessel, an absorbent solution in said vessel, said vessel having a chamber above said solution for holding gas, a floating piston 100 movable longitudinally of said chamber and normally separating the gas from said solution, valve means to permit the passage of the gas past said piston, said vessel having an orifice entering said chamber and connected to a source of gas and having an exit orifice, and valve means for closing said orifices, the outer end of said valve means forming substantially a continuation of the inner surface of said chamber. 110

7. A gas analyzer comprising a tubular vessel, an absorbent solution in said vessel, said vessel having a chamber above said solution for holding gas, a piston buoyantly carried by said solution and movable longitudinally of said chamber and normally separating the gas from said solution, valve means to permit the passage of the gas past said piston, said vessel having an orifice entering said chamber and connected to a source 120 of gas and having an exit orifice, means for causing a flow of gas through said orifices and said chamber, and means for closing said orifices, which substantially forms a continuation of the inner surface of said chamber. 115

8. A gas analyzer comprising a vessel having a closed chamber in the top thereof, an absorbent solution in said vessel, a piston fitting said chamber and adapted to float on 130

- 5 said solution, means normally disconnected from said piston for moving it upwardly through said chamber, a by-pass around said piston, said vessel having intake and exit orifices opening into said chamber, means for drawing a stream of gas through said orifices and valve means for closing said orifices flush with the surface of said chamber.
9. A gas analyzer comprising a vessel having a gas chamber, an absorbent solution in said vessel, a piston buoyantly carried by said solution and movable through said chamber, and means within said vessel and normally disconnected from said piston for moving it through said gas chamber.
10. A gas analyzer comprising a vessel, an absorbent solution held therein, said vessel having a chamber adjacent said solution, a piston normally separating said chamber from said solution, means whereby said piston is held at a predetermined distance above said solution, means for drawing a stream of gas through said chamber, valve means for holding a quantity of said gas in said chamber at atmospheric pressure, and means for by-passing said gas past said piston to contact with said solution.
11. In a gas analyzer comprising a vessel having a gas inclosing chamber, valve casings having bores communicating with said chamber, one of said casings having two adjacent side branches having passageways for communication with a source of gas and means for moving the gas respectively, a third side branch having a passageway, said casing having also an opening communicating with the atmosphere, a valve rod movable longitudinally of said casing, pistons on said rod adapted to close the said bore from said chamber, to place said adjacent passageways in communication and said third side branch in communication with the atmosphere, a side branch on the other of said casings having a passageway in communication with the passageway of said third side branch and a piston valve for closing the bore of said other casing after the valve of said first mentioned casing has operated.
12. A gas analyzer comprising a vessel having a gas chamber therein, an absorbent solution below said chamber, a piston fitting within said chamber and adapted to pass the contents of said chamber from one side of the piston to the other side, buoyant means for maintaining said piston out of contact with said solution, and means below the surface of said solution for operating said piston.
13. In a gas analyzer comprising a vessel having a closed chamber, an absorbent solution, means for drawing a continuous stream of gas from the source thereof through said chamber, said chamber having intake and exit openings, valve means for closing said openings flush with the interior surface of
- 5 said chamber and inclosing a quantity of gas from said stream at atmospheric pressure and by-passing said stream during the time said gas is inclosed, a piston movable longitudinally of said chamber, means to permit the flow of gas past said piston, and solution carrying devices on the underside of said piston for bringing said solution into contact with said gas.
14. In a gas analyzer comprising a vessel having a closed chamber, an absorbent solution, a piston movable longitudinally of said chamber and normally carried by buoyant devices at a predetermined distance above the surface of said solution, means to permit the passage of gas past said piston, said vessel having an intake orifice entering said chamber and connected to a source of gas, said vessel having an exit orifice, mechanical means for moving a continuous stream of gas, valve means for directing said stream of gas through said orifices, or for closing the same and by-passing the said stream, and means carried by said piston for carrying solution into said chamber.
15. In a gas analyzer comprising a vessel having a chamber, an absorbent solution in said vessel, a piston movable longitudinally of said chamber, buoyant means carried by said piston to support the underside thereof above said solution, means to permit the passage of gas from one side of said piston to the opposite side, said vessel having intake and exit orifices opening into said chamber, a fan adapted to move a continuous stream of gas, valve means for by-passing said stream of gas, closing said intake orifice and placing said exit orifice in communication with a body of gas at atmospheric pressure, valve means for closing said exit orifice, means for moving said piston upwardly through said chamber while said orifices are closed, and means for carrying solution into contact with the contents of said chamber when said piston moves upwardly.
16. In a gas analyzing device comprising a vessel, absorbent solution partly filling said vessel to form a chamber thereabove, a piston in said chamber with its underside buoyantly held at a predetermined distance above said solution, means for permitting the passage of gas past said piston, means for inclosing a quantity of gas in said chamber at atmospheric pressure, means passing through said solution for raising said piston so as to cause the contents of said chamber to pass to the underside thereof, and means carried by said piston for raising a quantity of the solution into contact with the gas under said piston.
17. In a device for analyzing gas comprising a vessel having a gas chamber therein, an absorbent solution below said chamber, a piston fitting within said chamber

and adapted to pass the contents of said chamber from one side of the piston to the opposite side, buoyant means causing said piston to float above said solution, and 5 means for moving said piston through said chamber.

18. In a device for analyzing gas comprising a vessel for holding an absorbent solution and having a closed chamber above 10 said solution for holding the gas, a piston movable longitudinally of said chamber, buoyant means carried by said piston for holding the underside thereof above said solution, by-pass means for permitting the 15 transfer of the contents of said chamber from one side of said piston to the opposite side, means for moving said piston, and means carried by said piston for carrying solution into contact with the gas as said 20 piston is moved upwardly.

19. In a gas analyzer comprising a vessel having a chamber an absorbent solution in 25 said vessel, a piston movable longitudinally of said chamber, buoyant means carried by said piston to support the underside thereof above said solution, means to permit the 30 passage of gas from one side of said piston to the opposite side, orifices opening into said chamber, a fan adapted to move a continuous stream of gas, valve means for bypassing said stream of gas, closing said in-

take orifice and placing said exit orifice in communication with a body of gas at atmospheric pressure, and means for closing 35 said exit orifice.

20. A gas analyzer comprising a vessel, an absorbent solution therein, said vessel having a chamber above said solution, a piston movable in said chamber, and means 40 for maintaining an invariable volume between the under side of said piston and the surface of said solution when said piston is in its lowermost position.

21. A gas analyzer comprising a vessel, an absorbent solution therein, said vessel 45 having an absorption chamber above said solution, means for inclosing a quantity of gas in said chamber, a piston normally separating said inclosed gas from said solution, and means for maintaining said piston 50 when in its lower position at an invariable distance above the surface of said solution.

22. A gas analyzer comprising a tubular vessel having a gas absorption chamber, said chamber having intake and exit orifices communicating therewith, valve means for closing 55 said orifices substantially flush with the surface of said chamber to inclose a quantity of gas and means for bringing gas into contact with an absorbent solution.

In testimony whereof I affix my signature.
SHIRLEY S. WEEKS.
